UNITED STATES PATENT OFFICE.

CARL RICHARD HIERONYMUS, OF NEW YORK, N. Y.

DESIGN FOR A FABRIC.

SPECIFICATION forming part of Design No. 13,949, dated May 29, 1883.

Application filed November 15, 1882. Term of patent 3½ years.

To all whom it may concern:

Be it known that I, CARL RICHARD HIERONYMUS, of New York, in the county and State of New York, have invented a new and original Design for Fabric, of which the following is a specification.

The accompanying drawing represents a face view of my new design.

This invention relates to a new ornamentation of woven fabric; and it consists in forming lines therein, as hereinafter described.

a b are sets of parallel lines, repeated at regular intervals on the face of the fabric.

Between the lines *b a* are lines *c d*, that are parallel to the lines *a b*. The line *c* has at regular intervals short cross-lines *e e*, and the line *d* has at regular intervals short cross-lines *f f*, the lines *e f* alternating, as shown.

I claim—

The design for a fabric, composed of the parallel lines *a b c d* and alternating cross-lines *e f*, substantially as shown.

CARL RICHARD HIERONYMUS.
